UNITED STATES PATENT OFFICE.

WILLIAM H. McLAUGHLIN, OF HARTFORD, CONNECTICUT, ASSIGNOR TO CASSIUS S. CHASE, OF HARTFORD, CONNECTICUT.

TRACTION DEVICE.

1,391,262.

Specification of Letters Patent. Patented Sept. 20, 1921.

Application filed July 13, 1917. Serial No. 180,328.

To all whom it may concern:

Be it known that I, WILLIAM H. McLAUGHLIN, a citizen of the United States, residing at Hartford, in the county of Hartford and State of Connecticut, have invented certain new and useful Improvements in Traction Devices, of which the following is a specification.

This invention relates to clamps or attaching means of the spring clip or clasp type, preferably of integral construction to be sprung over and across the felly of an automobile wheel and to be held against displacement by coöperating means carried by said felly, and is more particularly designed for use with the wheels of the lighter classes of pleasure and business automobiles.

The object of this invention is to provide a resilient metal clip or clamp having resilient hooks to receive the terminal links of an anti-skidding chain and which may be easily and quickly attached and detached without the use of any tools, and which need not employ any screws or similar fastenings to be manipulated each time the clip is applied or removed.

In the accompanying drawings:

Figure 1 represents a view in side elevation of a segment of a wheel with devices embodying my invention applied thereto;

Fig. 2, a sectional view on the line 2—2 of Fig. 1;

Fig. 3, a similar view, the tire being broken away, and one end of the clamp or clip free from its corresponding catch carried by the felly; and

Fig. 4, a detail perspective view of the clip alone.

Referring now in detail to the drawings, A represents the pneumatic tire of the wheel, B the rim, C the felly, and D the anti-skidding chain provided on each end with two rings or round links E.

The felly C is provided at intervals with pairs of nails or studs 1 having split points and driven into the felly from its sides, the nails 1 of each pair being driven in from diametrically opposite points of the sides of said felly so that they will have a common central longitudinal line.

The head of each nail 1 has a shoulder lying against the face of the felly, and has its outer face inclined inwardly toward the inner periphery of the felly C and is pro-

vided with a short lip 2 presented toward the rim B.

Spring clips or clamps 3 of elongated U-shape and preferably stamped or formed from a single piece of sheet metal and provided with slots 4 in their sides are adapted to be forced over said felly C, each side engaging and riding outwardly on the inclined face of the head of the corresponding nail 1 until the edge of its slot 4 passes beyond the edge of the lip 2, when it will snap inwardly against the side of the felly.

The bridge of the clip is to be made slightly longer than the width of the felly it is intended to be applied to, and the sides will be drawn in slightly toward each other to allow the clip as a whole to be slightly deformed, as stated, to get the edges of its slots 4 beyond the lips 2, when it will spring back into normal shape, drawing its sides toward the inner periphery of the felly so that the material of the sides of the clip adjacent the edges of the slots 4 will be drawn between the sides of the felly C and the lips 2 of the respective nails 1.

The sides of the clip or clamp 3 are bent outwardly back on themselves, to form hooks 5, the end portions of which are reduced in thickness, increasing their resiliency at this point. The end portions of these hooks 5 will be normally held, by their own resiliency, against the adjacent faces of the sides of the clip.

In practice, after these clips have been snapped on as above, rings E attached to the ends of an anti-skidding chain D and forming terminal links thereof will be snapped into the hooks 5 of each of said clips.

The material of said hooks 5 may be cut away as at 6, as shown, in order to better receive and position the coöperating rings E of the anti-skidding chains D.

Two such rings E are shown attached to each end of each chain to allow them to be adjusted in length to suit the cross-sectional measurements of the tire, rim and felly.

The inner face of the bridge of the clip or clamp 3 may be provided with a rubber treated textile lining F, as shown, to prevent marring of the inner peripheral face of the felly C.

To remove the clips it is simply necessary, in each instance, to unhook one end of the anti-skidding chain and pull it laterally of

the wheel, thus pulling the side of the clip 3, to which it is still hooked, away from the side of the felly C and free of the lip 2, as illustrated in Fig. 3, when its resiliency 5 will force it free from the felly C and the other lip 2.

Having thus described my invention, what I claim as new and desire to secure by Letters Patent is:

- 10 1. A resilient clip adapted to have positive engagement with a wheel felly and provided with a portion in arranged position extending across the inner peripheral face of the felly and with side portions having means 15 to receive respectively the terminal portions of an anti-skid or traction element, each side portion being provided with a face to engage a lug, the engaged face of which lies substantially in a plane transverse of the 20 wheel, whereby the resilient clip in applied relation will be held firmly against movement radially as a whole toward the hub of the wheel, but may be easily and quickly removed by a lateral pull on one of the side 25 portions.
2. A clip adapted to have positive engagement with a wheel felly and provided with a portion in arranged position extending across the inner peripheral face of the felly and with resilient side portions having means 30 to receive respectively the terminal portions of an anti-skid or traction element, each side portion being provided with a face to engage a lug, the engaged face of which lies substantially in a plane transverse of the 35 felly, whereby the clip in applied relation will be held firmly against movement radially as a whole toward the hub of the wheel, but may be easily and quickly removed by a 40 lateral pull on one of the side portions.
3. A wheel felly having parts permanently mounted therein and projecting from the respective lateral faces thereof, in combination with a resilient clip bridging said felly 45 and provided with portions respectively presented at angles to said lateral faces, said portions being provided respectively with means to receive the terminal portions of an anti-skid or traction element at points 50 radially from the hub beyond said projecting parts and being cut out to receive and be sprung over said projecting parts to hold

said clip against creeping movement relatively to the felly between the adjacent spokes of the wheel and against radial movement toward the hub of the wheel, the resiliency of the clip permitting its expeditious removal simply by a lateral pull on one of the side portions resulting in disengaging it from its respective projection.

4. A part having two faces and headed studs projecting from each of said faces and provided with lips, in combination with an integral resilient metal clip having portions adapted to engage said faces adjacent said 60 studs, said portions being adapted to receive said studs and engage the lips thereof and provided with means to receive an additional element.

5. A part having two faces and headed 70 studs projecting from said faces respectively and having their axes substantially in alignment and provided with lips, in combination with an integral resilient metal clip having two slotted portions adapted to engage said 75 faces and receive said studs and to fit between said lips respectively and the adjacent portions of said faces, said portions being provided with means to receive an additional element.

6. A wheel felly, in combination with a clip having resilient side portions engaging the opposite side faces of the felly, said felly and side portions being provided with positive interengaging means, the said side 85 portions of said plate being provided with means to removably receive the respective terminal portions of a traction element at points radially from the hub beyond said interengaging means, and a traction device 90 thus connected to said side portions of the clip, the device as a whole being removable by disengaging one of said resilient side portions of said clip by a lateral pull on one of the end portions of said traction element 95 after the disconnection of the other end portion thereof from said clip.

In testimony whereof, I have signed my name to this specification in the presence of two subscribing witnesses.

WILLIAM H. McLAUGHLIN.
